SINK MOUNTING

Lloyd L. Bair, Flint, Mich.

Application October 20, 1949, Serial No. 122,545

14 Claims. (Cl. 4—187)

1

This invention relates to plumbing fixtures and in particular to improvements in sink mounting and fastening means in conjunction with a drainboard or cupboard counter top.

Various mounting and fastening means are known and have been employed in securing a sink in sealed relation to a drainboard or cupboard counter top in the modern type building where the sink is mounted as part of an integrated built-in cupboard, counter top or drainboard.

Due to the confined working space and the "on the job" workman's problems, the various known mounting and fastening means for the sink have been found unsatisfactory due to the difficulty involved in installing them initially and then due to the difficulty of securing the fastening means in the confined space below the sink in the region of the cupboard.

With the foregoing in view, the primary object of the invention is to provide mounting and fastening means for installing a sink on a drainboard or counter top which are easily associable with the drainboard and the sink and which are easily fastened.

An object of the invention is to provide spaced extensions on the ribbed molding which extend below the bottom of the drainboard or cupboard top providing wedge receiving areas between the extensions and wedge cooperating structure in the area of the extensions.

An object of the invention is to provide a cross-foot or feet on either side of the spaced extensions constituting structural area suitable for riding a wedge thereon.

An object of the invention is to provide dual wedges having portions of different height adapted to ride on the extension cross-foot or cross-feet so that the relatively thick drainboard or cupboard top and the relatively thin sink flange are simultaneously contacted and secured by driving the wedges.

An object of the invention is to provide a cross-member or spanning member coupling the wedge portions of different height together to secure the wedge portions on the cross-feet and to provide a face for driving the wedge portions.

Another object of the invention is to provide a slot in the dual wedge members to receive the extensions therein to allow the wedge portions of different height on either side of the slot to enter into the area of the spaced extensions and cross-foot so that the wedge portions may ride on the cross-feet attached to the extensions.

Another object of the invention is to provide 55 20, a continuous rib 31 disposed between the

2

means for mounting and securing the sink on the drainboard or cupboard counter without the use of screws, bolts or nails.

These and other objects of the invention will become apparent by reference to the following description of the inventive sink mounting and fastening means in connection with the accompanying drawings, in which:

Fig. 1 is a top plan view of the invention in 10 conjunction with a drainboard or counter top and a sink.

Fig. 2 is a side elevational view of the invention taken on the line 2—2 of Fig. 1; a section being 15 partly broken away to illustrate the detail of the molding rib and the securing wedges.

Fig. 3 is a perspective view of the invention taken on the line 3—3 of Fig. 2.

Fig. 4 is a bottom plan view of the invention similar to Fig. 1.

20 Fig. 5 is an exploded view of the inventive ribbed molding and a securing wedge.

Fig. 6 is a side elevational view showing a wedge 25 driven in one direction in relation to the ribbed molding on the sink flange side of the ribbed molding.

Fig. 7 is a side elevational view showing a wedge driven in the opposite direction in relation to the ribbed molding on the sink flange side of the ribbed molding.

30 Fig. 8 is a perspective view of the inventive ribbed molding; and

Fig. 9 is a perspective view of an inventive securing wedge.

Referring to the drawing wherein like numerals 35 refer to like and corresponding parts throughout the several views, the inventive integrated sink, drainboard, mounting and securing means disclosed therein comprises a relatively thick drainboard or cupboard counter-top 20, a top 21 on the drainboard 20, a bottom 22 on the drainboard 20, a continuous internal peripheral edge 23 on the drainboard 20 describing and defining a sink receiving opening therein, a sink 24, a basin 25 on the sink 24, a continuous external relatively thin flange 26 on the sink 24 at the top of the basin 25 receivable within the sink receiving opening of the drainboard 20, a continuous external peripheral edge 27 on the sink flange 26

40 facing and spaced slightly away from the internal peripheral edge 23 on the drainboard 20, a top 28 on the sink flange 26 disposed level with the top 21 of the drainboard 20, a bottom 29 on the sink flange 26 disposed above the plane of bottom 22 of the drainboard 20, a ribbed molding

45 50 55 20, a continuous rib 31 disposed between the

internal peripheral edge 23 on the drainboard 20, a top 28 on the sink flange 26 disposed level with the top 21 of the drainboard 20, a bottom 29 on the sink flange 26 disposed above the plane of bottom 22 of the drainboard 20, a ribbed molding

drainboard internal peripheral edge 23 and the sink flange external peripheral edge 27 closing the space therebetween and lying level with the top 21 of the drainboard 20 but not extending to the bottom 22 of the drainboard 20 and lying level with the top 28 of the sink flange 26 and extending below the bottom 29 of the sink flange 26 but not extending below said counter bottom, a head 32 on the molding rib 31 overlying both the drainboard top 21 and the sink flange top 28, downwardly extending long flat spaced extensions 33 on the continuous rib 31 depending below the bottom 22 of the drainboard 20, side faces 34 on either side of the extensions 33, exposed wedge receiving ends 34 on the extensions 33 adjacent the spaces between the extensions 33, a cross-member 35 at the bottom end of the extensions 33 comprising a foot 36 on either side of the extensions 33 at right angles to the side faces 34 and extending co-extensively therewith, a slotted dual wedge 40 receivable into the longitudinal plane of the extensions 33 via the spaces between the extensions 33 and insertable into the area of the extensions 33 with the slot 41 of the dual wedge 40 receiving the extension 33 endwise therein, a high tapered portion 42 on the dual wedge 40, a top 43 on the high tapered portion 42 contacting the bottom 29 of the sink flange 26, a bottom 44 on the high portion 42 contacting the ribbed molding foot 36, a low tapered portion 45 on the dual wedge 40, a top 46 on the low tapered portion 45 contacting the bottom 22 of the drainboard 20, a bottom 47 on the low tapered portion 45 contacting the ribbed molding foot 36, a spanning portion or block 48 between the high portion 42 and the low portion 45 rigidly connecting same, and a face 49 providing driving or hammering area on the dual wedge 40.

The ribbed molding 30 provides the two confining or reaction points or members against which the action of the dual wedges 40 is exerted with the top resistance being provided by the head 32 and the bottom resistance being provided by the cross-foot 35 with each being immovably mounted in relation to the other by being connected together by the rib 31 and the extensions 33 so that they cannot be forced apart by the action of the dual wedges 40. The head 32 lies over the drainboard top 21 on one side and the sink flange top 28 on the other side while the wedging action of the dual wedge low portion 45 is exerted against the drainboard bottom 22 securing the ribbed molding 30 to the drainboard 20 and the wedging action of the dual wedge high portion 42 is exerted against the sink flange bottom 29 securing the sink 24 to the ribbed molding 30 and via the molding 30 to the drainboard 20.

In employing the inventive improvements in sink mounting and fastening means in conjunction with a drainboard or cupboard counter top, the applicator first constructs the drainboard or counter top 20 with a sink receiving opening therein described or defined by the continuous internal peripheral edge 23; he then inserts the ribbed molding 20 which has been manufactured to conform to the configuration of the peripheral edge 23 in the opening next adjacent the internal peripheral edge 23 with the head 32 overlying the top 21 of the drainboard 20 and with the rib 31 next adjacent the drainboard edge 23; he then brings the sink 24 up from under the drainboard 20 into the sink receiving opening therein until the top 28 of the sink flange 26 lies next adja-

cent the head 32 of the ribbed molding 30 so that the head 32 overlies the sink flange 26 and the sink flange external peripheral edge 27 lies next adjacent the rib 31; he then inserts a dual wedge 40 into the space between the ribbed molding extensions 33 with the high portion 42 of the wedge 40 on the sink flange 26 side of the rib 31 and the low portion 45 of the wedge 40 on the drainboard 20 side of the rib 31 and he then drives the wedge with a hammer securing the ribbed molding 30 to the drainboard 20 and the sink 24 to the ribbed molding 30 thereby supporting the sink 24 on the drainboard 20 via the ribbed molding 30 and the interlocking wedges 40.

The wedges 40 are preferably fabricated as right hand and left hand respectively so that their wedging action is exerted in opposite directions to prevent creeping and so that the driving of one wedge to tighten same acts to tighten its companion wedge previously driven in the opposite direction. Fig. 4 illustrates two preferred styles of associating the wedges 40 with the ribbed molding 30 with the smaller spaces able to receive a wedge 40 therein shown at the top of the figure, while larger spaces able to receive two wedges 40 are shown at the bottom of the figure.

The short cross-foot or cross-member 35 on the molding 30 allows the sink 24 to be brought up from under the drainboard 20 and pass the cross-foot 35 on the molding 30 as the ribbed molding 30, being unfastened, can tip or tilt slightly when the sink flange 26 is pushed past the cross-foot 35. After the sink is positioned, the ribbed molding 30 lies perfectly straight and level as no distorting influences are exerted on same.

Due to the fact that the ribbed molding 30 is fastened to the drainboard 20 and the sink 24 at exactly the same time and at points exactly oppositely opposed, all stresses and distorting influences on the molding 30 are counter balanced and neutralized leaving the molding 30 and especially the head 32 smooth and unrippled and in flat sealing relation to the drainboard 20 and the sink flange 26.

It can be seen from the foregoing description taken in conjunction with the accompanying drawing that a sink 20 can easily and quickly be mounted and secured on a drainboard or cupboard counter top 20 without the use of nails, screws, or bolts and that the installation can be made with facility regardless of cramped working conditions.

Although but a single embodiment of the invention has been shown and described in detail, it is obvious that many changes may be made in the size, shape, detail and arrangement of the elements of the invention within the scope of the appended claims.

I claim:

1. A sink integration comprising a drainboard, a top on said drainboard, a bottom on said drainboard, a continuous internal relatively thick peripheral edge on said drainboard describing a sink receiving opening therein, a sink, a continuous external relatively thin flange around the top of said sink receivable in the opening of said drainboard, a top on said flange level with said drainboard top, a bottom on said flange above the plane of said drainboard bottom, a continuous external peripheral edge on said flange facing said drainboard edge at the top thereof, a continuous rib disposed between said drainboard edge and said sink flange edge closing the space

therebetween, a head on said rib overlying both said drainboard top and said sink flange top, downwardly extending spaced extensions on said continuous rib depending below the plane of said drainboard bottom, side faces on either side of said extensions, ends on said extensions, a foot on either side of said extensions at the bottom of said faces, a top on said foot, a dual wedge member receivable into the plane of said rib extensions via the spaces between said rib extensions, a relatively low tapered wedge drainboard portion on said wedge slidably past said extension face, a bottom on said wedge drainboard portion riding on said extension foot top, a top on said wedge drainboard portion engaging said drainboard bottom gripping said drainboard between said rib head and said wedge drainboard portion securing said rib to said drainboard, a relatively high tapered wedge sink flange portion on said wedge slidably past said extension opposite face, a bottom on said wedge sink flange portion riding on said extension foot top, a top on said wedge sink flange portion engaging said sink flange bottom gripping said sink flange between said rib head and said wedge sink flange portion securing said sink flange to said rib, a bridge rigidly connecting said wedge drainboard portion and said wedge sink flange portion so that one said portion secures the other said portion in maintaining engagement with said foot tops and a face on said bridge providing hammering area to drive said wedge.

2. A sink integration comprising a drainboard, a top on said drainboard, a bottom on said drainboard, a continuous internal relatively thick peripheral edge on said drainboard describing a sink receiving opening therein, a sink, a continuous external relatively thin flange around the top of said sink receivable in the opening in said drainboard, a top on said flange level with said drainboard top, a bottom on said flange above the plane of said drainboard bottom, a continuous external peripheral edge on said flange facing said drainboard peripheral edge at the top thereof, a continuous rib disposed between said drainboard edge and said sink flange edge lying within said drainboard edge and outside said sink flange edge closing the space therebetween, a head on said rib overlying both said drainboard top and said sink flange top, spaced extensions on said continuous rib extending downwardly from said rib beyond the plane of said drainboard bottom, ends on said extensions; a foot on said spaced extensions projecting outwardly therefrom at either side thereof at right angles, the spaces between said extensions providing open area adjacent the ends of said extensions for inserting securing wedges, and dual wedge members receivable into the plane of said rib extension ends via the spaces therebetween and slidably endwise past the faces of said rib extensions into pressure engagement with said foot and said drainboard bottom on one side and said foot and said sink flange bottom on the other side.

3. A sink integration comprising a drainboard, a top on said drainboard, a bottom on said drainboard, a continuous internal relatively thick peripheral edge on said drainboard describing a sink receiving opening therein, a sink, a continuous external relatively thin flange around the top of said sink receivable in the opening in said drainboard, a top on said flange level with said drainboard top, a bottom on said flange above the plane of said drainboard bottom, a continuous external peripheral edge on said flange facing

said drainboard peripheral edge at the top thereof, a continuous rib disposed between said drainboard edge and said sink flange edge lying within said drainboard edge and outside said sink flange edge closing the space therebetween, a head on said rib overlying both said drainboard top and said sink flange top, spaced extensions on said continuous rib extending downwardly from said rib beyond the plane of said drainboard bottom, ends on said extensions; a foot on said spaced extensions projecting outwardly therefrom at either side thereof at right angles, the spaces between said extensions providing open area adjacent the ends of said extensions for inserting securing wedges, a dual wedge member receivable into the plane of said rib extensions via the spaces between said rib extensions, a relatively high tapered sink side on said wedge slidably past said extension face, a bottom on said side riding on said foot top, a top on said side engaging said sink flange bottom urging said sink flange top into pressure contact with said head whereby said strip is secured to said drainboard; a relatively low tapered drainboard side on said wedge slidably past said extension opposite face, a bottom on said side riding on said other foot top, and a top on said side engaging said drainboard bottom urging said drainboard top into pressure contact with said head whereby said sink is secured to said strip.

4. A sink integration comprising a drainboard having a sink receiving opening therein, a sink disposed in the opening of said drainboard, a flange on said sink level with said drainboard top, spaced slightly from the edge of said drainboard, a rib disposed between the edge of said drainboard and the edge of said sink flange closing the space level between said sink and said drainboard and lying level with the top of said drainboard and said sink flange, a head on said rib overlying both said drainboard and said sink flange, spaced extensions depending from said rib, a foot on said extensions on the drainboard side thereof, a foot on said extensions on the sink flange side thereof, dual wedge members having a slot for receiving said extensions therein adapted to engage said drainboard bottom and said extension foot on one side of said extensions to secure said drainboard between said head and said wedge; and to engage said sink flange bottom and said extension foot on the other side of said extensions to secure said sink flange between said head and said wedge.

5. A sink integration comprising a drainboard having a sink receiving opening therein, a sink disposed in the opening of said drainboard, a flange on said sink level with said drainboard top spaced slightly from the edge of said drainboard, a rib disposed between the edge of said drainboard and the edge of said sink flange closing the space and lying level with the top of said drainboard and said sink flange, a head on said rib overlying both said drainboard and said sink flange, spaced extensions depending from said rib, a foot on the drainboard side of said extensions, a foot on the sink flange side of said extensions, wedge members having a slot for receiving said extensions therein to allow said wedges to partially enter into the area of said extensions to the extent of the slot, a portion on said wedge riding on said drainboard extension foot engaging said drainboard and securing said drainboard between said wedge portion and said head, a second portion on said wedge riding on said sink flange extension foot engaging said sink

flange and securing said sink flange between said second wedge portion and said head.

6. A sink structure comprising a relatively thick drainboard having a sink receiving opening therein, a rib lining the opening of said drainboard flush with the top thereof and spaced slightly above the bottom thereof, spaced extensions on said rib extending below the bottom of said drainboard, a sink disposed within the opening of said drainboard, a relatively thin flange on said sink flush with said drainboard top and flush with and abutting said rib top, a head on said rib overlying said drainboard and said sink flange, a cross-foot on said extensions, a relatively thin wedge portion riding on said cross-foot engaging the bottom of said relatively thick drainboard working with said head to secure said strip to said drainboard, a relatively thick wedge portion riding on said cross-foot engaging the bottom of said relatively thin sink flange working with said head to secure said sink to said rib, and a block lying in the space between said extensions rigidly connecting said wedge portions so as to hold said wedges in contact with said cross-foot.

7. A sink structure comprising a relatively thick cupboard counter board, a top on said counter, a bottom on said counter, a continuous internal peripheral edge on said counter describing and defining a sink receiving opening therein, a sink disposed in the opening of said counter, a basin portion on said sink, a continuous external relatively thin flange on said sink at the top of said basin portion, a continuous external peripheral edge on said sink flange facing and spaced slightly away from said internal peripheral counter edge, a top on said sink flange disposed level with said top on said counter, a bottom on said sink flange disposed above the plane of said counter bottom, a continuous molding rib disposed between said counter edge and said sink flange closing the space therebetween and lying level with said counter top and said sink flange top and extending below said sink flange bottom but not extending below said counter bottom, a head on said molding rib overlying both said counter top and said sink flange top, downwardly extending spaced long flat extensions on said molding rib depending below said counter bottom, side faces on either side of said extensions, exposed wedge receiving ends on said extensions adjacent the spaces between said extensions, a cross-member at the bottom end of said extensions including a foot on either side of said extensions at right angles to said extension side faces and extending co-extensively therewith, a slotted dual wedge receivable into the longitudinal plane of said extensions via the spaces therebetween and insertable into the area of said extensions with the slot in said dual wedge receiving said extensions endwise therein, a high tapered portion on said dual wedge, a top on said high tapered portion adapted to contact a sink flange bottom, a bottom on said high tapered portion contacting said ribbed molding foot; said high tapered portion being adapted to wedge a sink flange top against said head to secure a sink to said molding rib; a low tapered portion on said dual wedge, a top on said low tapered portion adapted to contact a drainboard bottom, a bottom on said low tapered portion contacting said ribbed molding foot; said low tapered portion being adapted to wedge a drainboard against said head to secure said ribbed molding to a drainboard; said molding head, rib, extensions, and cross-members resisting the wedging action of said dual wedge providing top and bottom reaction points; a dual wedge spanning portion connecting said high and low wedge portions securing said portions in contacting relation to said cross-member, and a face on said high, low and spanning portions of said dual wedge for driving said dual wedge.

8. In a device as set forth in Claim 7, right and left hand dual wedges driven in opposite directions with their wedging action exerted in contacting relation to said cross-member, and a face on said high, low and spanning portions of said dual wedge for driving said dual wedge.

9. In a device as set forth in Claim 7, right and left hand dual wedges driven in opposite directions with their wedging action exerted in opposite directions so that the driving of one said wedge to tighten same acts to tighten its companion wedge previously driven in the opposite direction.

10. Sink to drainboard mounting and securing means comprising a continuous molding rib disposable between a drainboard edge and a sink flange edge to close the space therebetween and adapted to lie level with a drainboard top and a sink flange top and adapted to extend below a sink flange bottom and adapted to not extend below a drainboard bottom, a head on said molding rib adapted to overlie both a drainboard top and a sink flange top, downwardly extending spaced long, flat extensions on said molding rib adapted to depend below a drainboard bottom, side faces on either side of said extensions, exposed wedging receiving ends on said extensions adjacent the spaces between said extensions, a cross-member at the bottom end of said extensions including a foot on either side of said extensions at right angles to said extension side faces and extending co-extensively therewith, a slotted dual wedge receivable into the longitudinal plane of said extensions via the spaces therebetween and insertable into the area of said extensions with the slot in said dual wedge receiving said extensions endwise therein, a high tapered portion on said dual wedge, a top on said high tapered portion adapted to contact a sink flange bottom, a bottom on said high tapered portion contacting said ribbed molding foot; said high tapered portion being adapted to wedge a sink flange top against said head to secure a sink to said molding rib; a low tapered portion on said dual wedge, a top on said low tapered portion adapted to contact a drainboard bottom, a bottom on said low tapered portion contacting said ribbed molding foot; said low tapered portion being adapted to wedge a drainboard against said head to secure said ribbed molding to a drainboard; said molding head, rib, extensions, and cross-members resisting the wedging action of said dual wedge providing top and bottom reaction points; a dual wedge spanning portion connecting said high and low wedge portions securing said portions in contacting relation to said cross-member, and a face on said high, low and spanning portions of said dual wedge for driving said dual wedge.

11. In a device as set forth in claim 9, right and left hand dual wedges driven in opposite directions with their wedging action exerted in opposite directions so that the driving of one said wedge to tighten same acts to tighten its companion wedge previously driven in the opposite direction.

12. A sink integration comprising a drainboard having a sink receiving opening therein, a sink disposed in the opening of said drainboard, a flange on said sink level with said drainboard top, spaced slightly from the edge of said drainboard, a rib disposed between the edge of said drainboard and the edge of said sink flange closing the space between said sink and said

drainboard and lying level with the top of said drainboard and said sink flange, a head on said rib overlying both said drainboard and said sink flange, spaced extensions depending from said rib, a foot on said extensions on the drainboard side thereof, a foot on said extensions, on the sink flange side thereof, dual wedge members having a slot for receiving said extensions therein adapted to engage said drainboard bottom and said extension foot on one side of said extensions to secure said drainboard between said head and said wedge; and to engage said sink flange bottom and said extension foot on the other side of said extensions to secure said sink flange between said head and said wedge, and left hand dual wedges driven in opposite directions to prevent creeping and so that the driving of one said wedge to tighten same acts to tighten its companion wedge previously driven in the opposite direction.

12. Sink to drain board mounting means comprising a rib adapted to line the opening in a drainboard and to surround a sink disposed therein; said rib being adapted to extend below a sink and drain board; a head on said rib adapted to overlie a portion of a sink and drain board and a foot on the bottom of said rib providing a base upon which wedges are ridable to exert pressure against a sink and a drain board.

13. A drain board sink-mounting molding generally "I" shaped in cross-section comprising a rib adapted to lie between a sink and a drain board and to extend below both these members, a head on said rib overlapping on either side thereof adapted to overlie a sink-flange on one side of said rib and a drain board on the other 35

side of said rib, and a foot on the bottom of said rib extending sidewise outwardly on either side thereof; said rib and foot being interrupted at intervals to receive wedges to exert pressure on both a drain board and a sink flange by riding on said foot.

14. A drain board sink-mounting molding generally "I" shaped in cross-section comprising a rib adapted to lie between a sink and a drain board and to extend below both these members, a head on said rib overlapping on either side thereof adapted to overlie a sink-flange on one side of said rib and a drain board on the other side of said rib, and a foot on the bottom of said rib extending sidewise outwardly on either side thereof; said rib and foot being interrupted at intervals to receive wedges to exert pressure on both a drain board and a sink flange by riding on said foot, a dual wedge insertable in the area of said rib via the interruptions in said foot and rib adapted to ride on said foot to exert pressure on both a drain board and a sink flange.
